BOILER

Samuel Curtis, Dover, Mass.

Application April 27, 1937, Serial No. 139,192

1 Claim. (Cl. 122—149)

This invention relates to boilers, an object of the invention being to provide a boiler which constitutes either a steam boiler furnace or a furnace for heating water in hot water systems, and which includes a casing constituting a water chamber having an inlet at its lower portion and an outlet at its upper portion with a fire-box located in the upper portion of the casing, and having an improved arrangement of flues, fire tubes, and baffles which compel the burnt gases to travel downwardly in a circuitous path where they are carried off by a flue at the lower end of the furnace, while the water is compelled to travel upwardly in a circuitous path, the direction of movement of the water being opposite to the direction of movement of the gases.

The invention embodies many novel features of construction and combinations and arrangements of parts, all of which will be more fully 20 hereinafter described and pointed out in the claim.

In the accompanying drawings—

Fig. 1 is a view in vertical longitudinal section illustrating my improved boiler, and

Fig. 2 is a view in vertical transverse section, the view being taken on the staggered line 2—2 of Fig. 1.

10 represents the casing of my improved boiler which constitutes a water chamber, and the 20 front and rear or end walls 11 and 12 of the casing, in the lower portions of said walls, may have clean-out doors 13 as indicated in Fig. 1 of the drawings. Spaced from these end walls of the furnace are vertical plates 14 and 15, respectively, forming together with the end walls, smoke flues 16 and 17, respectively, the smoke flue 17 at its lower end communicating with the outlet flue 18 for carrying off the burnt gases.

The space between the plates 14 and 15 and 40 the major portion of the upper part of the casing constitute a water chamber having an inlet 19 in the lower portion of the casing and an outlet 20 at the upper portion thereof. The flues 16 and 17 are connected by fire tubes 21 which are, 45 of course, secured in the plates 14 and 15 and a superimposed series of horizontal partitions constituting baffles 22, 23 and 24 are provided in the boiler. The partitions or baffles 23 and 24 extend across the flues 16 and 17 and extend 50 into the water space between the smoke tubes 21. The upper partition or baffle 22 forms the upper end of flue 17 and also extends into the water space.

In the water space or water chamber above 55 the upper partition or baffle 22, my improved

auxiliary combustion chamber 25 is located and is surrounded by the water in the chamber. The front or forward end of this chamber 25 is in open communication with the flue 16, while the inner or rear end of this chamber 25 is a closed 5 end 26 which is of curved or general semi-cylindrical form.

This auxiliary combustion chamber 25 is preferably rectangular in cross section and within this chamber 25 my improved primary combustion chamber 27 is located. This primary combustion chamber 27 is also preferably of rectangular form and rests upon the lower wall of the chamber 25 so that a space is provided at the top and both sides of the combustion chamber which is in direct communication with the flue 16. The inlet end of the primary combustion chamber 27 is tapered or restricted in area forming an entrance member 28 which is closely connected with the front wall 11 of the furnace. 20 The upper wall of the primary combustion chamber 27 at its inner end is inclined downwardly, as shown at 29, and the sides of this combustion chamber 27 are preferably covered with suitable refractory material 30.

It is to be noted that the primary combustion chamber 27 terminates short of the inner end of the auxiliary combustion chamber 25 so that the burnt gases pass from the inner end of the primary combustion chamber 27 into the auxiliary combustion chamber 25 and are directed upwardly and laterally by contact with the curved end 26 of chamber 25 so that they pass around the three sides of the combustion chamber 27 into the flue 16.

The reference character 31 is employed to indicate generally an apparatus for directing air, preferably under pressure, into the inlet end of the primary combustion chamber 27, and 32 represents a nozzle which may constitute an oil 40 or gas nozzle. It is also to be understood that I may employ any fuel which is capable of use in the furnace.

33 represents a return pipe for conveying the steam and water of condensation, or only water 45 if the apparatus be a hot water heater, to the inlet 19, and I preferably employ a radiator 34 through which the returning steam and water pass before entering the inlet pipe. This radiator 34 is located in an air casing 35 having air inlets 36 at its lower end, and an air outlet flue 37 at its upper end communicating with the air entrance device 31 so that the returning steam and water serve to heat the air prior to its entrance into the combustion chamber.

55

The operation of the boiler is as follows: The flame from the burner 32 is directed into one end of the primary combustion chamber 27 and escapes through the inner end of said chamber 5 27 into the inner end of the auxiliary chamber 25 and is deflected around the combustion chamber 27 into the flue 16 down which the gases pass and are baffled by the baffle 23 and are compelled to pass longitudinally through the upper 10 set of tubes 21 into the upper portion of flue 17, and as this flue 17 is baffled by partition or baffle 24 the gases must then pass again longitudinally through the tubes 21 to the lower portion of flue 16, and thence again longitudinally 15 through the lower set of tubes to the lower portion of flue 17 from which they escape through the outlet flue 18. Water entering the inlet 19 flows upwardly through the water chamber and horizontally back and forth in a circuitous path 20 around the partitions or baffles 24, 23 and 22, and it will be noted, particularly by reference to Fig. 1, that the flow of the water is directly opposite to the flow of the burnt gases. Thus the water and gases are coldest at the lower portion of 25 the furnace and the temperature is increased to the upper portion where the greatest amount of heat units is contained.

While I have illustrated and described what I believe to be a preferred embodiment of my invention, it is obvious that various slight changes 30 may be made with regard to the form and ar-

rangement of parts without departing from my invention, and hence I do not limit myself to the precise details set forth but consider myself at liberty to make such changes and alterations as fairly fall within the spirit and scope of the 5 claim.

I claim:

A boiler, including a casing constituting a water chamber having a water inlet at its lower portion, down draft flues in the lower portion of the 10 casing, an auxiliary fire box disposed in the upper portion of the casing and having a closed end and an open end communicating with the flues, said auxiliary fire box fixedly secured in the casing at its open end only, its closed end 15 terminating short of the wall of the casing so that the auxiliary fire box is capable of free expansion and contraction, a primary fire box located in the auxiliary fire box and discharging at its inner end into the auxiliary fire box, the 20 primary fire box being preferably smaller than the auxiliary fire box and having a reduced end extending across a flue to permit the burnt gases in the primary box to pass through said flue, said primary box having its upper wall at 25 its inner end inclined downwardly so that the burnt gases are discharged into the lower portion of the auxiliary fire box and directed over the top of the primary fire box into the flue.
